UNITED STATES PATENT OFFICE.

CLINTON S. GOODYEAR, OF NAUGATUCK, CONNECTICUT, ASSIGNOR TO L. CANDEE & COMPANY, A CORPORATION OF CONNECTICUT.

HEELLESS OVERTSHOE.

1,176,286.

Specification of Letters Patent. Patented Mar. 21, 1916.

Application filed July 10, 1914. Serial No. 850,161.

To all whom it may concern:

Be it known that I, CLINTON S. GOODYEAR, a citizen of the United States, residing at Naugatuck, county of New Haven, and 5 State of Connecticut, have invented certain new and useful Improvements in Heelless Overshoes, of which the following is a full, clear, and exact disclosure.

My invention relates to rubber overshoes, 10 and more specifically to overshoes of the heelless type, and has for an object to provide a heelless overshoe which will not slip down at the back upon the inner shoe over which it is worn.

15 The counter of the ordinary heelless overshoe is constructed to tightly fit the counter of the inner shoe so that friction with the inner shoe counter will hold it in place. It has been found, however, that such frictional engagement is ineffectual in accomplishing its purpose, for when the wearer steps forward in walking the leather shoe has a tendency to push forward in the toe of the overshoe and thereby slacken the 20 counter, which consequently works down and must be pulled up from time to time. To obviate this annoyance, I provide the elastic counter of the overshoe with an integral elastic thickened foothold which ex- 25 tends above the top edge of the counter and has its excessive thickness disposed inwardly of the inner face of the counter. As a result of this construction the foothold will fit above the stiff counter of the inner shoe upon which 30 it may be worn, and due to its increased thickness will have greater tension under the same amount of stretch than the counter, thereby promoting the protrusion of the stiff counter underneath the foothold to sup- 35 port the foothold against slipping down, the tight seating of the foothold above the stiff counter being enhanced by the excessive thickness of the foothold existing inwardly of the inner face of the elastic counter.

40 The invention will be readily understood from the following description, reference being made to the accompanying drawing, in which:

Figure 1 is a side elevation of a lady's 45 shoe equipped with an overshoe embodying my invention; Fig. 2 is a side elevation of the last upon which the overshoe is built, with the overshoe shown thereon in section;

Fig. 3 is a fragmentary cross-sectional view 50 on the line 3-3, Fig. 1.

Referring to the drawing, 9 designates a lady's shoe to which the heelless overshoe 10 is applied. The overshoe comprises a lining 11, a vamp 12, a sole 13 which terminates at the rear end in a shank 14, a counter 15 the bottom edge 16 of which is free and co-acts with the free rear edge 17 of the shank in forming a heel opening, and a foothold 18 which extends above the top edge of the counter. The counter corresponds in 60 shape throughout to the shape of the stiff counter of the inner shoe over which the overshoe may be worn, that is, its upper edge is designed to follow along and conform to the entire edge contour of said stiff counter. 65 The foothold and counter are preferably formed of a single blank of material, the foothold being of greater thickness than the counter, and the excessive thickness of the foothold being disposed inwardly of the inner face of the counter so that the outer face of the counter and the outer face of the foothold are substantially flush with each other. The foothold is provided with beads 18' and 18" on the outer face, preferably formed in 70 integral with the foothold by engravings on the calender roll when the foothold is made. These beads serve to stiffen the foot hold against stretching at the top edge and at the juncture of the foothold with the counter 75 and provide an additional means independent of the thickness of the foothold, for causing the foothold at localized portions to bind against the inner shoe. Furthermore the bead 18" serves as a guide along which 80 the counter may be severed from the foothold when mutilated, leaving the overshoe equipped with a foothold similar to the ordinary foothold overshoe.

In building the overshoe the lining 11, 95 vamp 12, sole 13 and counter 15 with the attached foothold 18, are assembled upon a last 19, the same having a depression 20 in the vamp to receive the excess thickness of the foothold. The inner wall of this recess 100 gradually merges into the sides of the shank of the last and as a result of this the vamp and foothold will conform smoothly to the inner shoe shank or instep. The lining 11 is terminated slightly in the rear of the 105 shank of the sole, as shown at 21, the two-fold object of this being to leave the lower edge of the foothold completely exposed to better seat above the stiff counter of the inner shoe and to strengthen the joint at the 110

intersection of the sole and counter of the overshoe. The various materials mentioned are pressed into a compact homogeneous form and shaped to the configuration of the 5 last in the usual manner.

When a heelless overshoe, constructed as above described, is fitted over an inner shoe the elastic counter will fit the counter 21 of the inner shoe smoothly, while the elastic 10 foothold will fit the inner shoe above its counter, and by virtue of being of greater thickness than the elastic counter will have greater tension under the same amount of stretch than the elastic counter, whereby 15 the strain is concentrated upon the foothold. The pressure of the foothold will promote the tendency of the counter to protrude underneath the foothold and support the latter against slipping down, as best 20 shown in Fig. 3, the tight seating of the foothold above the stiff counter being enhanced by the excessive thickness of the foothold existing inwardly of the inner face of the elastic counter.

25 While I have described and illustrated a heelless overshoe embodying a counter and foothold attached to the counter, I do not limit myself to this construction, it being only essential to the practice of my invention 30 that the back of a heelless overshoe be so constructed as to fit the inner shoe tightly above its counter and fit smoothly over the inner shoe counter.

Having thus described my invention, what 35 I claim and desire to protect by Letters Patent is:

1. An overshoe having an elastic counter adapted to fit and conform to the outline of the counter of the inner shoe over which it 40 may be worn, and an elastic foothold extending above the top edge of the elastic counter and adapted to fit the inner shoe above its counter, the foothold being integral with and of greater thickness than the elastic 45 counter, and due to its increased thickness having greater tension under the same amount of stretch as the elastic counter, whereby the strain is concentrated upon the foothold when the overshoe is in use, and a 50 bead integral with the outer face of the foothold at its joint with the counter and stiffening the foothold at said joint to bind

against the inner shoe above the edge of the inner shoe counter and forming a guide along which the counter may be severed 55 from the overshoe when mutilated.

2. A rubber overshoe embodying a vamp, a sole terminating at the rear end in a shank, a counter, the bottom edge of the counter and the rear edge of the shank 60 being free and co-acting in defining a heel opening, said counter conforming in outline to the outline of the stiff counter of the inner shoe over which the overshoe may be worn, and a foothold extending above the 65 top edge of the counter, said foothold being integral with the counter and of greater thickness than the counter, the excessive thickness of the foothold existing inwardly of the inner face of the counter, and the 70 outer faces of the foothold and the counter being substantially flush with each other, and a bead integral with the outer face of the foothold at its joint with the counter and stiffening the foothold at said joint to 75 bind against the inner shoe above the edge of the inner shoe counter and forming a guide along which the counter may be severed from the overshoe when mutilated.

3. A rubber overshoe embodying a vamp, 80 a sole terminating at the rear end in a shank, a counter, the bottom edge of the counter and the rear edge of the shank being free and co-acting in defining the heel opening, said counter corresponding in 85 shape to the shape of the stiff counter of the inner shoe over which the overshoe may be worn, a foothold integral with the counter, vamp, and shank, and being of greater thickness than the counter, the joint between the foothold and counter being adapted to lie above and conform to the entire edge contour of the inner shoe stiff counter, and a bead disposed exteriorly of and reinforcing said joint and forming a guide 90 along which the counter may be severed 95 from the overshoe when mutilated.

Signed at New York, county of New York, State of New York, this 2 day of July, 1914.

CLINTON S. GOODYEAR.
